CALK DEVICE

Howard M. Pierce and John H. Hermson, Brook-
lyn, N. Y., assignors to A. G. Spalding & Bros.,
New York, N. Y., a corporation of New Jersey

Application June 13, 1938, Serial No. 213,428

12 Claims. (Cl. 36—59)

This invention relates to a calk device for attachment to a shoe sole, as for example to the sole of a shoe for use in football, soccer or other sport.

It is an object of the present invention to provide such a calk device which is of simple construction, easy to apply to a shoe sole, is rugged, and which will be very securely held in position on the shoe sole.

To the end of providing a satisfactory calk device which may be easily applied to a shoe sole, it heretofore has been proposed to form a calk device comprising an internally threaded bushing insertable in an aperture in a shoe sole and in which the threaded stem of a calk or cleat is screwed.

It is an object of the present invention to provide a calk device which includes a gripping means for preventing an inadvertent unscrewing of the calk.

In achieving the above object there is provided as a feature of the invention a calk device including a novel internally threaded tubular insert for the sole, having a single means which not only serves to overlap and grip the underside of the shoe sole but also serves to grip the base of the calk so as to maintain the calk against inadvertent unscrewing.

Another feature of the invention resides in forming the internally threaded insert with fingers which are clinched over to grip the underside of the sole and which are formed to provide gripping teeth for engaging the calk and holding the same against inadvertent unscrewing.

A complementary feature to the above resides in providing a bushing insertable on the internally threaded tubular member which serves to facilitate a proper clinching of the radial gripping fingers and serves also to more securely maintain the fingers in clinched position.

Other objects and features will hereinafter appear.

In the drawing:

Figure 1 is an exploded view showing the various elements of the calk device before association with the shoe sole, a portion of the insert member being broken away to enable a clearer illustration.

Fig. 2 is a sectional view showing the calk device in operative association with the shoe sole.

Fig. 3 is a view looking toward the underside of the shoe sole, showing the novel calk-holding insert of the device in operative position, prior to the application of the calk.

Fig. 4 is a view showing the base of the calk.

Fig. 5 is a view similar to Fig. 4 but showing a modified form of a calk.

Before describing the present improvements and mode of operation thereof in detail it should be understood that the invention is not limited to the details of construction and arrangement of parts shown in the accompanying drawing, which are merely illustrative of the present preferred embodiments, since the invention is capable of other embodiments, and the phraseology employed is for the purpose of description and not of limitation.

Referring more particularly to the drawing and first to Figs. 1 through 4, there is shown a section of a shoe sole 10 of conventional construction, having an inner layer 11 and an outer layer 12, and having a usual calk-device-receiving aperture 13 formed therein.

The calk device 14 provided by the present invention includes a calk or cleat 15 which may be formed of hard rubber or any other suitable material. As shown, this calk is of generally frustoconical shape and has a base 16 from which extends, in a well-known manner, a screw-threaded stem 17.

To secure the calk 15 to the sole there is provided a novel insert member 18 having a main tubular section 19 with screw threads 20 formed interiorly thereof, and terminating at one end in a plurality of radially extending clinched gripping fingers 21 which, when the main section 19 is inserted in the aperture 13, overlap the bottom 22 of the shoe sole 12.

Of particular importance, and as shown most clearly in Figs. 2 and 3, certain of these fingers are laterally inclined to provide raised portions 23 extending longitudinally of the fingers and constituting gripping teeth 24 adapted to engage and bite into the base 16 of the calk 15 to hold the latter securely against inadvertent unscrewing when drawn toward the sole by the cooperation of the threaded stem 17 and the internally threaded tubular insert 18.

Preferably, as shown in Fig. 3, alternate radially extending fingers 21 are thus laterally inclined to provide the calk-gripping teeth 24 and all of the radially extending fingers are formed at their free ends with portions 25 turned so as to grip and bite into the underside 22 of the sole. Thus, the radially extending fingers 21 provide a single means for not only gripping the sole and thus securely holding the insert 18 relative thereto, but also for gripping the calk 15 and holding the same against inadvertent unscrewing.

To facilitate the proper clinching of the radially extending fingers 21 and to more securely maintain them in clinched position, there is ad-

vantageously provided a bushing 26 having a tubular main section 27 and an annular flange 28, which is placed on the internally threaded insert member 18 so that the flange 28 overlaps the underside 22 of the sole adjacent the aperture 13, and underlies the radially extending fingers 21. The sole-gripping portions 25 of the fingers 21 are bent over the peripheral edge of the bushing flange 28.

10 As shown in Fig. 1, the insert member 18 is initially formed, at the end remote from the flange 28, with a preferably unthreaded tubular section 30 constituting an integral continuation of the main threaded section 20. It is from this 15 continuing section 30 of the insert that the radially extending fingers 21 are formed.

When it is desired to associate the calk device 14 with the shoe sole, the insert member 18, in the form shown in Fig. 1, is placed in the aperture 13 so that the flange 28 rests on the upper side 31 of the sole 11 and the continuing section 30 projects outwardly from the underside 22 of the sole 12. The flanged bushing 26 is then placed on the continuing section of the insert member and pushed inwardly to rest upon the sole. Then by means of a suitable tool the continuing section is concurrently scored or lanced longitudinally to define the gripping fingers 21 and the fingers clinched downwardly to assume 30 the configurations shown in Figs. 2 and 3.

While the scoring or lancing and the clinching of the gripping fingers 21 are described above as being performed concurrently, it will be readily appreciated that the scoring or lancing operation may be performed either prior to or after the placing of the insert in the aperture 13, and the clinching of the fingers performed subsequently as a separate operation.

Whether or not the clinching operation be performed concurrently with or subsequent to the scoring or lancing operation, the bushing 26 serves to so confine and support the insert that the bending or clinching of the gripping fingers will not split the threaded section, and serves 45 also to provide a means whereby the clinched fingers will be so bent as to be securely maintained in clinched position. Also, the flanged bushing 26 serves to provide a means for facilitating the formation of the sole-gripping portions 25 at the free ends of the radially extending 50 fingers 21.

Preferably, and as shown, a plurality of circumferentially spaced projections 32 are formed on the flange 28 of the insert to grip and bite 55 into the upper side 31 of the sole and thus prevent adverse turning of the insert 18 relative to the sole.

Complementing the projections 32 in preventing adverse turning of the insert 18, there may be provided also a plurality of ribs 33 extending longitudinally of the insert 18 from the flange 28 and terminating short of the extremity 60 of the main threaded section. In addition to serving as a means to prevent adverse turning of the insert relative to the sole 10, these ribs 33 provide shoulders 34 which support bushing 26 and thus arrest longitudinal movement of the latter on the insert 18 during the clinching operation.

70 To complete the association of the calk device with the shoe sole, the threaded stem 17 is screwed into the threaded insert to draw the base 16 of the calk firmly against the gripping teeth 24.

75 As shown most clearly in Fig. 2, a central re-

cess 35 to receive the gripping fingers 21 is formed in the base 16 of the calk of such a depth that when the calk is screwed tightly in place not only will the teeth 24 bite into that portion of the base 16 constituting the bottom 36 of the recess, but also the peripheral outer portion 37 of the base will be held firmly against the underside 22 of the sole.

With the novel calk device 14 provided by the present invention, therefore, the insert 18 is securely held relative to the sole by the flange 28 and the radially extending gripping fingers 21, and these latter fingers in addition to serving as means for securing the insert 18 to the sole serve also as a means for gripping and holding the 10 calk 15 against inadvertent unscrewing. Also, of importance, the lateral bending and inclination of certain of the radially extending fingers 15 to form the calk-gripping teeth 24, provides in effect spring sections 23 which when compressed 20 by the calk serve to press on the base 16 of the calk and thus supplement the biting action of the teeth 24 in maintaining the calk against inadvertent unscrewing.

It is thus seen that the present invention provides a novel calk device 14 which is simple in construction, which is designed to be easily applied, and which when associated with the shoe sole is securely locked in place.

As shown in Fig. 5, a modified calk 15a may 30 be utilized. It is of substantially the same construction as the calk 15 first described, having a threaded stem 17 projecting from the base 16. Also as in the calk 15, the modified calk 15a has a central recess 35a formed in the base so that 35 the outer peripheral portion 37 thereof may be drawn tightly against the shoe sole.

However, and of importance, there are formed on the bottom 36a of the recess 35a in the base 16, a plurality of radially extending ribs 38 40 adapted to cooperate with the gripping teeth 24 in further securing the calk against inadvertent unscrewing.

While in describing the preferred embodiments of the invention only one calk device has been 45 shown as attached to a shoe sole, it will be appreciated that any number of such devices may be used and may be spaced in any desired manner.

Variations and modifications may be made 50 within the scope of this invention, and portions of the improvements may be used without others.

Having thus described the invention what is claimed as new is:

1. An insert for securing a calk to a shoe sole, 55 comprising a tubular member insertable in an aperture in a shoe sole, having internal threads cooperable with a complementary threaded means for drawing a calk toward said sole; and a single means on said tubular member for gripping said calk against inadvertent unscrewing.

2. An insert for securing a calk to a shoe sole, comprising a tubular member insertable in an aperture in a shoe sole, having internal threads 65 cooperable with a complementary threaded means for drawing a calk toward said sole; and a plurality of radially extending fingers on said tubular member, formed to overlap and grip said sole and to grip and hold said calk against inadvertent 70 unscrewing.

3. An insert for securing a calk to a shoe sole, comprising a tubular member insertable in an aperture in a shoe sole, having internal threads cooperable with a complementary threaded 75

means for drawing a calk toward said sole; a bushing on said threaded tubular member; and a single means on said threaded tubular member for holding the bushing in place and gripping said sole, and for gripping and holding said calk against an inadvertent unscrewing.

4. A calk device, comprising an internally threaded tubular member insertable in an aperture in a shoe sole; flange means on said tubular member at one end thereof; a calk having a threaded stem screwed in said tubular member; and a single means on said tubular member, co-operable with said flange means to secure said tubular member to said sole, and engageable with said calk to grip and hold the latter against inadvertent unscrewing.

5. A calk device, comprising an internally threaded tubular member insertable in an aperture in a shoe sole; a calk having a threaded stem screwed into said tubular member; and a single means on said tubular member having portions for gripping said sole to hold the member against inadvertent rotation relative to the sole, and having projections for gripping and holding said calk against inadvertent unscrewing.

6. A calk device, comprising an internally threaded tubular member insertable in an aperture in a shoe sole; a calk having a threaded stem screwed into said tubular member; a plurality of radially extending fingers on said tubular member and adapted to overlap the underside of said sole, at least one of said fingers having a projecting portion engageable with said calk to grip and hold the same against inadvertent unscrewing.

7. A calk device, comprising an internally threaded tubular member insertable in an aperture in a shoe sole; a calk having a threaded stem screwed into said tubular member; a bushing on said tubular member; and a plurality of radially extending fingers on said tubular member, clinched over said bushing, at least one of said fingers having a portion formed to bite into said sole and at least one of said fingers being laterally inclined to provide a longitudinal edge engageable with said calk to grip and hold the same against inadvertent unscrewing.

8. In a calk device, comprising an internally threaded tubular member insertable in an aperture in a shoe sole; a calk having a threaded stem screwed into said tubular member; means on said tubular member for engaging said sole to maintain the member against rotation relative thereto; and a plurality of radially extending fingers on said tubular member, adapted to lap the under-

side of said sole, at least one of said fingers being formed to provide a gripping tooth for engaging said calk and holding the same against inadvertent unscrewing.

9. A calk device, comprising an internally threaded tubular member insertable in an aperture in a shoe sole; a calk having a threaded stem screwed into said tubular member; a bushing on said tubular member; a plurality of radially extending fingers on said tubular member, clinched over said bushing, at least one of said fingers being laterally inclined to provide a longitudinal edge engageable with said calk to grip and hold the same against inadvertent unscrewing; and means on said tubular member for arresting longitudinal movement of said bushing thereon and into said sole when the radially extending fingers are clinched.

10. A calk device, comprising an internally threaded tubular member insertable in an aperture in a shoe sole; a calk having a threaded stem screwed into said tubular member; projecting means on the base of said calk; and a single means on said tubular member having portions for gripping said sole to hold the member against inadvertent rotation relative to the sole, and having projections for engaging said projecting means on said calk to grip and hold the latter against inadvertent unscrewing.

11. A calk device, comprising an internally threaded tubular member insertable in an aperture in a shoe sole; a calk having a threaded stem screwed into said tubular member, said calk having a recess in the base thereof and encircling said threaded stem; and a plurality of radially extending fingers on said tubular member, positioned in said recess and adapted to overlap the underside of said sole, at least one of said fingers having a projecting portion engageable with said calk to grip and hold the same against inadvertent unscrewing.

12. A calk device, comprising an internally threaded tubular member insertable in an aperture in a shoe sole; a calk having a threaded stem screwed into said tubular member; and a plurality of radially extending fingers on said tubular member and adapted to overlie said sole, at least one of said fingers being laterally inclined to provide a portion engageable with said calk to grip and hold the same against inadvertent unscrewing, and having a portion formed to bite into said sole.
